UNITED STATES PATENT OFFICE.

WILLIAM JOHN FREDRICK WEGÉ, OF ST. PETERS, SOUTH AUSTRALIA, AUSTRALIA,
ASSIGNOR TO THE "WEGÉ" MOTOR LIMITED, OF ADELAIDE, SOUTH AUSTRALIA,
AUSTRALIA.

TWO-STROKE INTERNAL-COMBUSTION ENGINE.

Application filed November 18, 1920. Serial No. 425,013.

To all whom it may concern:

Be it known that I, WILLIAM JOHN FREDRICK WEGÉ, a subject of the King of Great Britain and Ireland, residing at 67 Third Avenue, St. Peters, State of South Australia, Commonwealth of Australia, have invented a certain new and useful Two-Stroke Internal-Combustion Engine, of which the following is a specification.

10 This invention comprises a two-stroke internal combustion engine for use with oil, petrol, alcohol, benzine or other volatile fuel, and is especially adapted for use in motor cars, aeroplanes and motor cycles.

15 It is very simple in construction and in operation and has no valves other than port valves. All valve operating gears consisting of cams, camshafts, tappets, tappet rods, rockers, valve guides, valve timing wheels, 20 and springs have been eliminated.

In order that my invention may be clearly understood I will describe the same with reference to the accompanying drawings in which I have shown in Figs. 1, 2, 3 and 4 25 a single block of three cylinders, and in Fig. 5 two such blocks placed at an angle of 60°. In Figs. 1 and 5 I have shown the crank shaft and crank case for two blocks forming a 6 cylinder engine.

30 Fig. 1 is a central vertical longitudinal section upon line *a b* of Fig. 3 of the cylinders and crank case but showing the pistons in full.

Fig. 2 is a central vertical longitudinal section, also upon line *a b* of Fig. 3, of the cylinder casting only, showing in dotted lines the position of the several passages.

35 Fig. 3 is a plan view of the cylinder casting only.

40 Fig. 4 is a horizontal section upon line *c d* of Fig. 2 of the cylinder casting only, showing the inlet ports and passages for the gaseous mixture and the outlet ports and 45 passages for the burnt gases.

Fig. 5 is a central vertical cross section 50 of the crank case and two blocks of cylinders and pistons.

As shown in the drawings each of the 55 cylinders comprises two parts 5 and 6 arranged in tandem, the part 5 of smaller diameter forming the power cylinder, and the part 6 of larger diameter forming the induction and compression cylinder. The induction and compression cylinder strictly

speaking is an annular chamber which is 55 formed between the cylinder wall and the smaller piston as the latter moves downward from the power cylinder during each stroke.

The power cylinders are enclosed within 60 a water jacket 7 with water outlet 8 and suitable inlet not shown, and at the top of each cylinder is an opening fitted with a priming plug 10.

The pistons are of the trunk type. Each 65 of them comprises two parts 11 and 12 corresponding to the two parts 5 and 6 respectively of the cylinder, the part 11 forming the power piston and the part 12 forming the induction and compression piston. 70 The smaller portion 11 has several piston rings 13 set into it near its outer end, also a baffle 14 preferably formed as an integral portion of the casting projecting from its top or outer face upon the side which passes the inlet port 16. The rings 13 not only prevent loss of power but also prevent the passing of gases from the power cylinder 5 to the compression cylinder 6. The baffle 14 directs the incoming charge of mixture 75 to the top of the cylinder thereby forcing out the burnt gases.

The larger portion 12 of the piston has 80 a ring 17 set into it near its outer end, also an extended sleeve 18 fitting within the cylinder. The ring 17 not only ensures effective suction and compression in the cylinder 12 but also prevents the passage of mixture into the crank case 20. Except 85 when the piston is at the bottom of its stroke the sleeve 18 closes the induction port 19. It prevents any communication between the carburettor and the crank case 20. The effect of this construction is that 90 the gaseous mixture does not at any time enter the crank case, nor is any air drawn therefrom, nor does any compression take place in the crank case.

The several pistons are connected to the 95 crank shaft 21 by connecting rods 22.

The induction port 19 whereby the gaseous mixture is admitted to the induction and compression cylinder 6 from the carburettor is situated in the lower part of the wall of the cylinder, and the induction ports 19 of the several cylinders are connected with the carburettor by means of an induction passage 23 in the wall of the unit. In 100 105

Fig. 5 I have shown the induction passages 23 of the two units connected by a horse-shoe shaped pipe 24 with a flange 25 for the attachment of the carburettor.

5 At the outer end of each compression cylinder is a gaseous mixture delivery port 15 whereby the mixture is delivered from the compression cylinder, these ports being connected by passages in the wall of the unit 10 with gas inlet ports 16 near the lower end of the power cylinders 5. The compression cylinder below power cylinder No. 1 delivers mixture to power cylinder No. 2, that below No. 2 delivers to No. 3 and that 15 below No. 3 delivers to No. 1. The exhaust port 26 of each power cylinder is positioned near the bottom of same on the opposite side to the inlet port 16 and slightly nearer the outer end of the cylinder than the inlet 20 port is.

The oil pump which supplies or circulates the necessary lubricating oil to my engine is mounted upon the wall of one of the compression cylinders. It comprises two concave cups 27 with a diaphragm 28 of suitable flexible material such as leather, or very thin metal clamped between them. The chamber at one side of the diaphragm 30 communicates with a check valve 29 having intake and delivery ball valves 30 and 31 and having suitable pipe connections therefrom to the oil supply and to the crank troughs of the engine respectively. These connections are not shown in the drawings. 35 The chamber at the other side of the diaphragm 28 communicates with the cylinder at about the centre of same so that the diaphragm is operated by the alternate suction and compression therein.

40 The engine is fitted with a carburettor of any approved type and with a magneto of the ordinary high tension type driven from the engine shaft. The mixture in each cylinder is fired by a sparking plug of any approved type secured in the opening 32.

The crankshaft is of the three throw type with the cranks set at angles of 120°. That shown in the drawings carries two piston rods on each throw. It is supported by four 50 hanging bearings to which oil is supplied by big end dippers.

The operation of my engine is as follows:—

Upon the firing of a charge in No. 1 55 power cylinder the piston is driven downward and a partial vacuum is caused in the induction and compression cylinder until the piston therein uncovers the induction port 19 whereupon gaseous mixture flows from the carburettor along the induction pipe 23 and into the cylinder. Simultaneously 60 the power piston, as it nears the bottom of its stroke, uncovers the discharge port 26 and the inlet port 16.

65 The burnt gases escape from the port 26

and compressed mixture flows from compression cylinder No. 3 along the passage and through the port 16 into the power cylinder No. 1 thus assisting the escape of burnt gases.

Upon its upstroke the power piston closes the ports 26 and 16 and as it rises it further compresses the mixture and when it reaches the top the mixture is fired by the sparking plug. Simultaneously the induction and compression piston closes the induction port 19 and the mixture is compressed in the compression cylinder from which it is (a little later—when the piston No. 2 descends) delivered through the outlet port 15 and along the connecting passage and through the inlet port 16 to the power cylinder No. 2. The several operations of the piston transmit alternate suction and compression impulses to the diaphragm 28 of the pump thus causing it to be sufficiently deflected by each stroke to promote and maintain a circulation of the lubricating oil.

Similar operations take place in the other cylinders.

It is also pointed out that the enlarged portion or extended skirt portion of each piston projects into the crank case and consequently is covered with oil splashed in the crank case or with oil mist present in the crank case. With this in view it is obvious that the oil pump could be dispensed with. It should be further here noted that the period of vacuum in each compression or induction cylinder is greater than the period of compression in said cylinder; and that consequently the oil splashed on the portion of the extended skirt which projects into the crank case is drawn up into said cylinder and transferred to the mixture into the respective power cylinder and thus eliminating any possibility of the oil being forced back into the crank case on the compression stroke.

What I claim is:—

A two-stroke internal combustion engine having splash lubrication and having cylinders each comprising two portions of different diameters and arranged in tandem, the part of smaller diameter in each instance being most distant from the crank shaft and forming the power chamber, and the part of larger diameter forming the induction and compression chamber, the walls of the cylinders having communicating ports whereby the compression chamber of the one cylinder is connected with the power chamber of another cylinder, and an extended skirt upon each compression piston adapted to extend into the crank case as the said piston moves to the bottom of its stroke, so that the outer wall of the projecting portion of the said skirt becomes covered with oil splashed in the crank case, the period of vacuum being greater than the period of compression.

and continuing until the extended skirt has projected into the crank case, so that the oil is thereby drawn up from the said extended skirt into the compression cylinder and 5 transferred with the mixture to the respective power cylinder.

In testimony that I claim the foregoing as

my invention I have signed my name in the presence of two subscribing witnesses this fourth day of October, 1920.

WILLIAM JOHN FREDRICK WEGÉ.
